COMBINATION BRUSH AND SQUEEGEE APPLICATOR

Herbert A. Siemund, Skokie, Ill., assignor to Greenview
Manufacturing Company, Chicago, Ill.

Filed May 19, 1964, Ser. No. 80,043

Term of patent 14 years

(Cl. D9—2)

FIG. 1

The dominant features of my design reside in the portions shown in full lines.

I claim:

The ornamental design for a combination brush and squeegee applicator, substantially as shown and described.
